SCREW STARTER

John Donald Olson, Kensington, and Wojciech Stanislaw Gutowski, Southington, Conn., assignors to The Stanley Works, New Britain, Conn.

Filed Feb. 14, 1972, Ser. No. 226,381

Term of patent 14 years

Int. Cl. D8—05

U.S. Cl. D8—86

FIG. 1

FIG. 2

FIG. 3

FIG. 4

FIG. 5

FIG. 6

FIG. 1 is a perspective view of a screw starter showing our new design;

FIG. 2 is a plan view thereof;

FIG. 3 is a side elevational view thereof, the opposite side being substantially a mirror image thereof;

FIG. 4 is a bottom view thereof;

FIG. 5 is a jaw end elevational view thereof; and

FIG. 6 is an elevational view of the opposite end thereof to a greatly enlarged scale.

We claim:

The ornamental design for a screw starter, as shown and described.
